To all whom it may concern:

Be it known that I, RITA M. The figure is a perspective view of a table ornament showing my new design.

This design is preferably made of paper,

although it can be made of any other suitable material, and is intended to be placed on the table at parties and such functions, and is ornamented in the fashion shown to simulate a Christmas tree. If desired, a light can be placed within the ornament for the purpose of illuminating the transparency thereon.

I claim:

The ornamental design for a table ornament as shown and described.
